UNITED STATES PATENT OFFICE.

HENRY L. FERRIS, OF HARVARD, ILLINOIS, ASSIGNOR TO HUNT, HELM, FERRIS & COMPANY, OF HARVARD, ILLINOIS, A CORPORATION OF ILLINOIS.

MANGER.

1,095,148.

Specification of Letters Patent. Patented Apr. 28, 1914.

Application filed June 9, 1913. Serial No. 772,610.

To all whom it may concern:

Be it known that I, HENRY L. FERRIS, a citizen of the United States, residing at Harvard, in the county of McHenry and State of Illinois, have invented a new and useful Improvement in Mangers, of which the following is a specification.

My invention relates to certain new and useful improvements in mangers and is fully described and explained in the specification and shown in the accompanying drawings, in which—

Figure 1 is an end view of my improved device, showing the same in its normal or lowered position in solid lines and in its raised position in dotted lines, and Fig. 2 is a section on the line 2, of Fig. 1.

Referring to the drawings, 3 is the curb of the stall; 4 is a trough of cement or other material forming the bottom of the manger, and, in accordance with common practice, extending longitudinally of a series of stalls; 5 is one of the vertical members of the stall-ends and 6 is one of the side bars of the stall, all these parts being formed in accordance with common and standard practice.

7 is a bar extending upward from the curb and diagonally forward at a slight inclination, its upper end being attached to a forward projection of the stall-side and its lower end being held firmly in position by any suitable mechanism. In the present form of construction the lower end of the bar 7 enters a hole in a casting 8 set in the concrete of the curb and forming the support for the frames at the front of the stall. It will be understood that a series of these bars 7 is provided, one opposite each stall-side, or between each two stalls in the series, as well as at the ends of the terminal stalls of the series. Each bar 7 carries a collar 9 vertically adjustable by means of a set-screw 10 and provided with a forwardly-extending vertical ear 11. These ears afford means for pivotally supporting manger partitions and ends 12, each of which is made of sheet-metal, stiffened at its edges with iron, and curved at its bottom to conform to the trough forming the bottom of the manger.

The partitions and ends are connected by a manger-front 13 of sheet-metal, so that when lowered each manger has a bottom formed by the trough, a front and two ends, but is open at the top and rear.

Surrounding each bar 7, above the collar

9, is a spring 14. Each of said springs presses upwardly upon collars 15 connected by links 16 with a point on the corresponding partition below and in front of the pivot thereof. The result is that these springs tend to raise the entire manger structure but they are of such a strength as compared to the weight of the mangers that when the latter are down their weight will hold them down. However, when the mangers are raised by hand, the rise is greatly assisted by the springs and, as the mangers rise, the pivot between the link and the manger-partition swings away from a straight line connecting the pivot of the link on the collar with the pivot of the partition on the ear 11, whereby the effective leverage of the spring is greatly increased. It will be noted that in the position shown in solid lines in Fig. 1, the link is quite close to the dead-center and its upward pull on the mangers is very slight, while in the position shown in dotted lines, the link has just moved past a position at right-angles to the line connecting its pivot on the partition with the pivot of the partition on the ear, so that the operation of the spring is very effective. Thus, the mangers remain in their lowered position, but when raised by hand are held up positively by the springs and their rise is facilitated throughout by the action of the springs.

It is to be observed that in the present form of construction the manger is pivotally supported entirely independent of the frame at the front of the stall. This frame, carrying as it does, a stanchion, and being longitudinally adjustable in the manner and for the purpose set forth in the application of myself and Howard J. Ferris, filed October 18, 1911, Serial No. 655,344, is wholly unfitted, by reason of its adjustment, to support the manger, which must necessarily occupy a position fixed with reference to the curb. Heretofore it has been the practice to mount pivoted mangers on the framework forming the front of the stall. In the present structure this practice is not followed, but the manger is carried entirely by other parts of the structure.

I realize that considerable variation is possible in the details of the construction herein shown, and I do not intend to limit myself thereto, except as pointed out in the following claims, in which it is my inten-

tion to claim all the novelty inherent in the device as broadly as is permitted by the state of the art.

I claim as new and desire to secure by Letters Patent,—

1. The combination with the stall-members, of a series of stalls and a manger in front of the stalls and pivotally movable, of bars extending upwardly at the margins between the stalls and serving pivotally to support the manger, springs surrounding the bars, and links, each having operative connections at one end with the manger and at the other with the spring, for the purpose set forth.

2. In combination, a curb, a frame forming the front of the stall and adjustable longitudinally of the stall with reference to the curb, a feed-partition member pivotally supported independent of the frame at the front of the stall and adapted to be raised and lowered, whereby the front frame of the stall may be longitudinally adjusted without changing the position of the feed-partition member.

3. In combination with stall-members and

upwardly-extending bars, springs surrounding the same, a sliding collar above each spring against which the same bears, a manger pivoted on the bars, and links connecting the collars with the manger at one side of the pivotal support of the manger, whereby the springs tend to raise the manger with increasing force as the same is raised.

4. In a manger and stall construction, in combination, a support, two frames mounted thereon, one of which is fixed and the other one of which is adjustable in the direction of the length of the stall, a manger pivotally mounted on the fixed frame and adapted to be raised and lowered, and spring operated means having a substantially dead-center position when the manger is in lowered position, and adapted to aid in raising the manger and hold it in raised position.

In testimony whereof I have hereunto set my hand this 3d day of April, 1913.

HENRY L. FERRIS.
